UNITED STATES PATENT OFFICE

2,498,763

MAGNETRON

John W. McNall, East Orange, N. J., assignor to
 Westinghouse Electric Corporation, East Pittsburgh, Pa., a corporation of Pennsylvania

Application June 15, 1944, Serial No. 540,453

11 Claims. (Cl. 250—27.5)

1

This invention relates to magnetrons and more particularly to tuning means therefor.

An object of the invention is to provide an improved and convenient means for tuning a magnetron.

Another object is to provide for a wide range of tuning for a magnetron.

A further object is to provide a rotative or oscillatory tuning means and with its axis of movement coincident with the axis of the cathode and anode.

A still further object of the invention is to provide a simple, light and readily assembled rotor for the tuning means.

Further objects of the invention will appear to those skilled in the art to which it appertains both by direct recitation thereof as the description proceeds and by inference from the context.

Referring to the accompanying drawing in which like numerals of reference indicate like parts throughout the several views;

Figure 1 is a cross section of a magnetron in which my invention is employed, the section being taken just below the end plate and longitudinally of the tuning control means.

Figure 2 is a section on line II—II of Fig. 1;

Figure 3 is a cross section on line III—III of Fig. 2;

Figure 4 is a perspective view of the rotor constituting an essential part of the invention;

Figure 5 is a cross section of one of the rotor vanes; and

Figure 6 is a cross section of a modified construction of rotor vane.

In the specific embodiment of the invention illustrated in said drawing, the reference numeral 10 designates a magnetron body portion shown as cylindrical, of metal, and closed by metallic end plates or caps 11. The particular magnetron here shown provides a plurality of internal radially disposed fixed metallic vanes 12 of less length than the cylindrical interior of the body portion so as to leave end spaces 13 between the ends of the vanes and the end plates 11. Said fixed vanes have their inner longitudinal edges separated from each other and directed toward a cylindrical centralized cathode 14 having usual internal heating filament 15. The vanes converge toward each other, viewed from the exterior, and thus define between successive vanes of the annular series thereof cavities having approximately trapezoidal cross-sectional shape, and for convenience of reference referred to as the resonant cavities 16. The region around the cathode and within the inner edges of the several

2

vanes is herein designated the cathode cavity 17. The fixed vanes, and particularly the inner edges thereof, constitute the anode. Input for the filament 15 is by way of lead-in structures 18 of usual construction, and output for derived energy is by way of a coaxial line 19 which is shown having an appropriate loop 20 in one of the resonant cavities.

In carrying out the present invention, the tuning means includes a rotor, shown alone in Fig. 4, said rotor being fabricated with two parallel rings 21, which may be either of metal or of insulator material, centered on a common axis, which in use is coaxial with the axis of the cathode and anode of the magnetron. When the rotor is assembled in the magnetron, said rings are within the aforementioned end spaces 13. Extending between the rings, in parallelism to the said axis, are a plurality of metallic vanes 22 evenly spaced in an annular series and in radial planes, except that there may be omission of or modification of one vane of the rotor corresponding to the cavity having the output loop, but otherwise there is shown one vane on the rotor for each resonant cavity of the magnetron. The number of vanes employed, however, may be varied as desired. The rotor vanes are carried at their ends by and revolved, with restricted amplitude, by the said rings. All rotor vanes have the same relation to their respective resonant cavity walls at any given position of the rotor, and rotation of the rotor makes a corresponding change of position for all of said rotor vanes with respect to the fixed vanes. For instance, one position of the rotor vanes is shown in solid lines in Fig. 3 and another position thereof is shown by adjacent dotted lines. Furthermore, the rotor vanes are free of contact from the cylindrical wall of the magnetron body, and have a width less than that of the fixed vanes so as not to project into the central or cathode cavity. The said rotor vanes are each likewise quite thin and may be made with opposite faces parallel as shown in Figs. 1 to 5, or may be a vane 22a, which is tapered in cross section as shown in Fig. 6, in which event the thicker edge is parallel to and next the cylindrical wall of the body portion. If desired, the rotor vanes may be covered with a dielectric material, such as mica or glass, to increase the capacity between rotor and fixed vanes and prevent sparking therebetween.

The rotor has, as a part thereof, a spider mount at each end, each said mount having a hub 23 from the periphery of which radiate several wire legs 24, outer end portions of which

are bent into parallelism with the hub axis and in a direction toward the ring of the rotor. These end portions of said legs 24 are embedded in, riveted to or otherwise secured to the said ring. Preferably, the said legs are electrically discontinuous one from another to avoid setting up induction current flow, and are shown each embedded separately in the hub which is indicated as of insulating material. Projecting axially outward from the hub 23 is a pivot pin 25, the projecting end of which is shown seated in a bushing 26 carried at the middle of the inner face of end plate or cap 11.

In order to rotatively adjust the rotor, either clockwise or counterclockwise, a lever 27 is shown as having an inner forked end engaging the bent leg portion of one of said spider legs 24, said lever projecting in a generally radial direction from engagement with said leg to a distance outside of the magnetron body. Said lever, however, is enclosed within a housing 28 which includes a flexible portion 29 by which vacuum sealing of the magnetron interior is maintained but permitting said lever to pass to the exterior and be there under control of the operator.

Inasmuch as said lever must be held securely in adjusted position, retaining as well as adjusting means are provided for the purpose. As shown, the lever has a head 30 thereon to which flexible housing portion 29 is secured and also on which is secured a bracket 31 which provides a forked end laterally of the lever. A sleeve 32 extending in the same general direction as the lever is pivotally carried by said forked end so as to swing in the same plane in which the lever swings. Longitudinally through the sleeve, and in threaded engagement therewith, is an adjusting screw 33 having a ball and socket connection with a bracket 34 fixed with respect to the magnetron. The outer end of the adjusting screw has a knurled knob 35 or other convenient manipulation means.

It is believed the theory of tuning by shifting the rotor vanes into different relations with respect to the fixed vanes or cavity walls will be in accordance with the following two possible explanations. First, as a rotor vane is brought closer to a fixed wall of the cavity resonator, the capacity between said wall and vane will be increased. Change of capacity will result in a change in the resonant frequency of that cavity resonator, thereby changing the frequency of the oscillations generated by the magnetron. Secondly, the tuning or rotor vanes and supporting ring or rings have a resonant frequency so that oscillations which may be generated therein react with the normal oscillations of the cavity resonators resulting in a change of frequency of the latter oscillations, and hence of the oscillations generated by the magnetron.

I claim:

1. In a magnetron having a circular series of cavity resonators, and having intervening walls separating said resonators, tuning means for said magnetron comprising a vane within one of said resonators and extending in the same general direction as the said intervening walls bounding that one of said resonators and movable in its entirety in parallelism to itself to closer proximity to one intervening wall than to the other intervening wall of the resonator in which said vane is located.

2. In a magnetron having a cavity resonator, tuning means comprising a vane in said cavity resonator extending substantially from end to

end of said resonator dividing the resonator space into two parts, and means at an end of said resonator supporting said vane, said means being rotatable in a direction normal to the vane for revolving said vane within the confines of said resonator and thereby changing the ratio of the two parts of the resonator space.

3. In a magnetron having a cavity resonator, tuning means comprising a vane in said cavity resonator extending substantially from end to end of said resonator dividing the resonator space into two parts, means at an end of said resonator supporting said vane, said means being rotatable in a direction normal to the vane for revolving said vane within the confines of said resonator and thereby changing the ratio of the two parts of the resonator space, and adjustable means in operative engagement with said vane supporting means for rotating said means and revolving said vane.

4. In combination with a magnetron having an axis and having a plurality of cavity resonators longitudinally parallel to the axis of the magnetron, tuning means therefor comprising a rotor having vanes disposed longitudinally in said resonators parallel to said axis and substantially in planes with said axis, said rotor having limited amplitude of rotation and all of said vanes being fixed in relation to each other and simultaneously movable with correspondingly limited amplitude in said resonators in which they are disposed.

5. Tuning means for a magnetron comprising a rotor having a ring, a hub coaxial with said ring, legs extending from said hub to said ring, and vanes fixed on said ring and rotatable therewith.

6. Tuning means for a magnetron comprising a plurality of rings in spaced parallel planes and centered on a common axis perpendicular to said planes, hubs offset outwardly from said planes and coaxial with said axis, legs connecting each hub with one of said rings, and vanes extending longitudinally between said rings and fixed at their ends to said rings.

7. Tuning means for a magnetron comprising a plurality of rings in spaced parallel planes and centered on a common axis perpendicular to said planes, hubs offset outwardly from said planes and coaxial with said axis, coaxial pins on the hubs projecting outwardly from each for rotative support thereof, legs connecting each hub with one of said rings, and vanes extending longitudinally between said rings and fixed at their ends to said rings.

8. Tuning means for a magnetron comprising a plurality of rings in spaced parallel planes and centered on a common axis perpendicular to said planes, hubs of insulative material offset outwardly from said planes and coaxial with said axis, legs connecting each hub with one of said rings, and vanes extending longitudinally between said rings and fixed at their ends to said rings.

9. In combination with an enclosure of an electron discharge device and a movable part within said enclosure, an operating mechanism for said movable part comprising a housing projecting from and secured to said enclosure, said housing having an opening longitudinally therethrough, a lever in and longitudinal of said opening and pivoted to said housing, a flexible sleeve sealed at one end to the housing and sealed at its other end to the outer end of the lever, thereby enabling vacuum to be maintained in

said enclosure and housing and enabling said lever to be swung exterior to the housing and operate said movable part within the enclosure.

10. In combination with an enclosure of an electron discharge device and a movable part within said enclosure, an operating mechanism for said movable part comprising a housing projecting from and secured to said enclosure, said housing having an opening longitudinally therethrough, a lever in and longitudinal of said opening and pivoted to said housing, a flexible sleeve sealed at one end to the housing and sealed at its other end to the outer end of the lever, thereby enabling vacuum to be maintained in said enclosure and housing and enabling said lever to be 15 swung exterior to the housing and operate said movable part within the enclosure, and means attached to the outer end of the lever for both swinging said lever and holding the lever in position to which swung.

20. In combination with an enclosure of an electron discharge device and a movable part within said enclosure, an operating mechanism for said movable part comprising a housing projecting from and secured to said enclosure, said housing having an opening therethrough, a lever in and projecting from said opening of the housing into the interior of said enclosure and in operative engagement with the part therein to be moved, and said lever projecting to the exterior of said housing through said opening, 25

means pivoting said lever to the housing, and means flexibly connecting the lever at an exteriorly projecting part thereof to said housing and providing a vacuum tight seal for the opening through the housing, said flexible means enabling said lever to be swung and at the same time maintain the vacuum therein and in the housing and enclosure.
